US00D859796S

(12) United States Design Patent (10) Patent No.: US D859,796 S
McLellan et al. (45) Date of Patent: * Sep. 17, 2019

(54) SHOE

(71) Applicant: Allbirds, Inc., San Francisco, CA (US)

(72) Inventors: Jamie McLellan, Auckland (NZ);
Timothy Brown, San Francisco, CA (US); Joseph Zwillinger, Mill Valley, CA (US)

(73) Assignee: ALLBIRDS, INC., San Francisco, CA (US)

() Term: 15 Years

(21) Appl. No.: 29/571,548

(22) Filed: Jul. 19, 2016

(51) LOC (12) Cl. 02-02
(52) U.S. Cl. D2/944

(57) CLAIM

The ornamental design for the shoe, as shown and described.

DESCRIPTION

FIG. 1 is a perspective view of a shoe, showing our new design;

FIG. 2 is a right side view thereof;

FIG. 3 is a left side view thereof;

FIG. 4 is a top view thereof;

FIG. 5 is a bottom view thereof;

FIG. 6 is a front view thereof; and,

FIG. 7 is a back view thereof.

The dashed lines are included for illustrating environmental structure and form no part of the claimed design.

1 Claim, 7 Drawing Sheets
